GRINDING DEVICE

Henry J. Perazzoli, Philadelphia, Pa.

Application October 25, 1934, Serial No. 749,974

17 Claims. (Cl. 51—178)

This invention relates to new and useful improvements in grinders and more particularly to grinders for the traction surfaces of railway track rails and the like.

5 The principal object of the invention is to provide an apparatus or device of the character set forth, having novel abrasive means operatively associated therewith to permit relatively high grinding speeds and at the same time effectually grind 10 a substantially large area of the traction surface of the rail.

A further object of the invention is to provide a device of the character set forth having novel abrasive means associated therewith in the form 15 of an endless chain of abrasive or grinding bricks.

A further object of the invention is to provide a device of the character set forth having novel abrasive means comprising a continuous chain of pivotally connected bracket elements and abrasive elements removably mounted therein.

20 Certain other objects and features of the invention and the details of the construction thereof are set forth hereinafter and shown in the accompanying drawings, in which:

25 Fig. 1 is a view in side elevation showing a portion of a grinding device with the abrasive mechanism forming the subject of the present invention associated therewith.

Fig. 2 is an enlarged view in section taken substantially on line 2—2, Fig. 1.

30 Fig. 3 is a view in perspective of one of the brackets in which the abrasive bricks are mounted.

Fig. 4 is a view in perspective of a brick having 35 a head associated therewith for mounting in the bracket disclosed in Fig. 3.

Fig. 5 is a view in perspective of the means for retaining the abrasive element in operative relation with its supporting bracket; and

40 Fig. 6 is a view in section longitudinally through the series of pivotally connected brackets mounted therein.

Heretofore, devices of the present character for grinding the surfaces of track rails have in almost 45 every instance been provided with abrasive elements of the circular rotating disk or reciprocating brick type. In the former or rotating disk type of abrasive element, while relatively high grinding speeds are attainable, the surface area 50 of the rail surface contacted thereby for grinding is relatively small, whereas in the reciprocating brick type, the surface area of the track rail ground by the bricks is considerably greater than that in the case of the circular rotating element, but the relative grinding speeds of the reciprocating

5 bricks are highly restricted because of the periodic alternate change in the direction of movement thereof.

By the present invention the provision of an endless chain of connected abrasive elements in 10 the manner disclosed herein, permits maximum grinding speeds and at the same time enables a substantially large surface area of the track rails to be ground or finished.

15 Referring now more particularly to the drawings, reference numerals 1, 1 designate the longitudinal frame members of the customary railway track grinder disposed in parallel spaced relation adjacent one side of the machine as shown in Fig. 2, and members 2 are secured between said frame 20 members 1, 1 transversely with respect thereto by means of bolts 3, the said members 2 being relatively spaced apart with respect to each other as shown in Fig. 1. Tubular sleeve bearings 4 are mounted vertically in the members 2 adjacent the transverse ends thereof inwardly of the longitudinal frame members 1 of the grinding machine.

25 In the present instance rods 5 are slidably mounted in the sleeve bearings 4 and have their upper ends secured in a common element or plate 6 by means of bolts 7. Jack screws 8 are threaded in sleeves 9 mounted in the member 6 and have their lower ends connected to the transverse members 2. The threads of the jack screws 8 are meshed with the internal threads of worm 30 wheels 10, mounted at the upper side of the member 6, and each worm wheel 10 is arranged to engage a worm 11 mounted upon a shaft 12 which is journaled in bearings 13 secured to the top of the members 6 by means of one of each 35 of the pairs of aforementioned bolts 7. As shown in Fig. 1 of the drawings the shaft 12 may be rotated from either end thereof by means of hand wheels 14.

40 The lower ends of each pair of slides rods 5 constitute supports 15 and 16 respectively for a shaft or axle 17 rotatably journaled in the former support 15 by means of a bearing 18 and in the support 16 by means of a pair of roller bearings 19 relatively separated by means of sleeves 20. 45 A sprocket 21 is mounted on the outer or left-hand end of the shaft 17 with respect to Fig. 2 and secured thereon by means of a nut 22, the said shaft 17 being secured against longitudinal displacement at its other end by means of a washer 50 23 and nut 24.

55 A plate or arm 25 extends between the lower end portions 16 of the corresponding slides rods 5 and the lower ends 15 of the slides rods 5 at the other ends of the members 2. A plurality

of supporting elements 26 are secured to each of the plates 25 and are disposed vertically with respect thereto in relatively spaced relation. Upper and lower transverse plates 27 and 28 respectively are secured substantially horizontally between the sets of supporting members 26 adjacent the upper and lower ends thereof by means of bolts 29. Also secured to the sets of supporting members 26 are upper and lower sets 10 of longitudinal guide channels 30 and 31.

A drum 32 is keyed to each of the shafts 17 for rotation therewith and sprockets 34 are also mounted on said shaft 17 at each side of the drum 32 and secured to the latter by means of bolts 35. It will be noticed by reference to Fig. 1 of the drawings that the aforementioned upper and lower horizontal plates 27 and 28 extend between the drums 32 and are so arranged that their end portions are disposed tangentially 20 with respect to the circumference of the said drums. It will further be noted that as seen in Figure 1, the end portions of the lower guide 28 are slightly inclined with reference to the mid-portion thereof and the rails to be ground, 25 this being of importance for reasons noted herebelow. In the present instance an endless chain A of contiguous rollers 36, pivotally connected together by means of links 37, extends about the drums 32 and is adapted to ride through its 30 lateral extent upon the outward surfaces of the upper and lower transverse plates 27 and 28. An outer chain B is adapted to ride upon the contiguous roller chain previously described and comprises a series of bracket elements 38 having 35 oblique undercut portions 39 extending transversely at the underside thereof, and a projection 40 at one end of the bracket of less width than said bracket, the said projection having a rounded external surface as at 41 and being provided with a transverse bore 42 located centrally with respect to the said projection 40. The 40 opposite ends of the brackets 38 are provided with spaced projections 43 having aligned apertures 44 therein, so positioned as to align with the bore 42 in the projection 40 of the next succeeding bracket 38 when in substantially abutting or contiguous relation. A pin 45 is passed through the apertures 44 in the projections 43 and the bore 42 in the projection 40 of the next succeeding bracket 38 to pivotally connect the same 45 together to form an endless chain as indicated and shown in Fig. 1 of the drawings.

In the present instance rollers 46, having circumferentially projecting flanges 47, are mounted upon every fourth pivot pin 45 and arranged for engagement by the teeth 48 of the sprocket wheels 34 previously described. Rollers 49 are also mounted upon these same pivot pins 45 at the ends thereof and outwardly with respect 50 to the aforementioned rollers 46. In the present instance the rollers 49 are rotatably mounted upon the pivot pins 45 by means of roller bearing assemblies 50, and are adapted to travel in the sets of the upper and lower guide channels 30 and 31 respectively during travel of the outer chain through its substantially horizontal exten- 55 tents intermediate the drums 32.

Movement is supplied to the chains A and B previously described by one of the drums 32 and 60 its associated sprockets 34 respectively mounted on one of the shafts 17, through the sprocket 21 mounted on one of the shafts 17 and driven by a chain 51 from a motor M mounted upon the member 6.

75 In the present instance, the abrasive elements

are of the customary brick form and comprise a body of abrasive material 52 which is molded or cast during manufacture into a head or cap element 53 having at its upper face a projection 54 the sides of which are undercut as at 55, the 5 said projection 54 and the undercut sides 55 thereof having such dimensions as to permit the same to fit snugly within the undercut recess 39 formed in the outer surfaces of bracket elements 38. With the abrasive brick and its integral cap 10 53 mounted in the undercut recess 39 of the bracket 38 the same is secured therein by means of a downwardly projecting lug 56 held in retaining position by means of a bolt 57 which may be screwed into the threaded opening 58 in that 15 side of the bracket 38 which will be at the outside of the mechanism with respect to the rails of the track, so that the abrasive element may be readily removed and replaced at the will of the operator of the machine. 20

The abrasive elements 52 may be adjusted relatively with respect to the traction surface of the track rails by rotation of the shaft 12 by the hand wheels 14 in alternate directions, thus raising or lowering the jack screws 8 and in turn the rods 25 5 which support the shafts or axles 17 upon which the abrasive means is mounted. In the present instance the plates 27 and 28 and guide channels 30 and 31 extending horizontally between the drums 32 at the upper and lower sides 30 thereof function to insure uniform contact pressure of the abrasive elements 52 in accordance with the degree of pressure as desired and regulated by means of the adjustment of the jack screws 8. 35

As hereinbefore noted, the end portions of guide 28 are inclined downwardly from the points of tangency with drums 32. By virtue of this construction, as is indicated in Figure 1, the sections or bricks 52 of the abrasive material approach 40 and leave the rail very gradually. To further bring out the advantage of this arrangement it might be noted that if guide 28 were straight throughout its length, each brick in moving from this straight guide onto the drum 32, or vice versa, 45 would become rather sharply cocked or angled, in consequence of which the advance and rear edges of the bricks would very rapidly become worn and therefore would not present a flat surface for contact with the rail during travel of the bricks along 50 the portion of the guide 28 intermediate its angled ends.

It might further be noted that because of the arrangement shown in Figure 1 and referred to just above, this grinding equipment in effect combines the action of a planer (in the region of the straight intermediate portion of guide 28) and the action of a rotating abrasive wheel (in the region of the drums 32). 55

While the details of construction and specific features of the invention have been set forth for the purpose of description, it is not intended that the same be limited thereto but that changes and modifications may be made without departing from the spirit of the invention where within the 60 scope of the annexed claims. 65

What I claim is:

1. In a grinding device, a main frame structure, a second frame structure supported by said main frame structure, drums rotatably mounted 70 in said second frame structure in spaced relation to each other, a sprocket mounted coaxially with one of said drums, horizontal plates mounted on the second frame structure and extending tangentially between the drums at the top and bottom 75

thereof, an endless chain of rollers arranged to travel on said drums and the intermediate plates, an outer endless carrier including a plurality of brackets arranged to travel on the chain of rollers, 5 pivots connecting the brackets in the outer carrier, means on certain of said pivots arranged for engagement by the teeth of the sprocket, upper and lower guide means, means mounted on certain of said pivot pins arranged to cooperate with 10 said guide means, abrasive elements mounted in the brackets of the outer chain, and means for actuating at least one of the drums to drive the carrier.

carrier.

2. In a grinding device, a main frame structure, a second frame structure supported by said main frame structure, means for adjusting the second frame vertically with respect to the main frame, drums rotatably mounted in the second frame structure in spaced relation to each other, sprocket associated with one of said drums and rotatable therewith, horizontal plates mounted on the second frame structure and extending tangentially between the drums at the top and bottom thereof, an endless chain of rollers arranged to travel on said drums and intermediate plates, an outer endless carrier including a plurality of brackets arranged to travel on the chain of rollers, pivots connecting the brackets of the outer carrier, means on certain of said pivots arranged for engagement by the teeth of the sprocket, upper and lower guide means, abrasive elements mounted in the brackets of the outer chain, and means for actuating the sprocket to drive the carrier.

actuating the sprocket to drive the carrier.

3. In a grinding device, a main frame structure, a second frame structure supported by said main frame structure, means for adjusting the second frame vertically with respect to the main frame, drums rotatably mounted in the second frame structure in spaced relation to each other, 35 sprocket associated with one of said drums and rotatable therewith, horizontal plates mounted on the second frame structure and extending tangentially between the drums at the top and bottom thereof, an endless chain of rollers arranged to 40 travel on said drums and intermediate plates, an outer endless carrier including a plurality of 45 brackets arranged to travel on the chain of rollers, pivots connecting the brackets of said outer carrier, means on certain of said pivots arranged 50 for engagement by the teeth of the sprocket, abrasive elements mounted in the brackets of the outer chain, and means for actuating the sprocket to drive the carrier.

4. In a grinding device, a main frame structure, a second frame structure supported by said main frame structure, means for adjusting the second frame vertically with respect to the main frame, drums rotatably mounted in the second frame structure in spaced relation to each other, 55 sprocket associated with one of said drums and rotatable therewith, horizontal plates mounted on the second frame structure and extending tangentially between the drums at the top and bottom thereof, an endless chain of rollers arranged to 60 travel on said drums and intermediate plates, an outer endless carrier including a plurality of brackets arranged to travel on the chain of rollers, pivots connecting the brackets in the outer carrier, upper and lower guide means, means mounted 65 on certain of said pivot pins arranged to cooperate with said guide means, abrasive elements mounted in the brackets of the outer chain, and means for actuating the sprocket to drive the 70 carrier.

75 5. In a grinding device, a main frame struc-

ture, a second frame structure supported by said main frame structure, means for adjusting the second frame vertically with respect to the main frame, drums rotatably mounted in the second frame structure in spaced relation to each other, sprockets associated with said drums and rotatable therewith, horizontal plates mounted on the second frame structure and extending tangentially between the drums at the top and bottom thereof, an endless carrier including a plurality of brackets arranged to travel about the drums, pivots connecting the brackets in the carrier, means on certain of said pivots arranged for engagement by the teeth of the sprockets, upper and lower guide means, means mounted on certain of said pivot pins arranged to cooperate with said guide means, abrasive elements mounted in the brackets of the carrier, and means for actuating at least one of the drums and its associated sprocket to drive the carrier.

6. In a grinding device a main frame structure, a second frame structure supported by said main frame structure, means for adjusting the second frame vertically with respect to the main frame, drums rotatably mounted in the second frame structure in spaced relation to each other, horizontal plates mounted on the second frame structure and extending tangentially between the drums at the top and bottom thereof, an endless chain of rollers arranged to travel on said drums and intermediate plates, an outer endless carrier including a plurality of brackets arranged to travel on the chain of rollers, pivots connecting the brackets in the outer carrier, upper and lower guide means, means mounted on certain of said pivot pins arranged to cooperate with said guide means, abrasive elements mounted in the brackets of the outer chain, and means for actuating at least one of the drums to drive the carrier. 25 30 35 40

7. In a grinding device, a main frame structure, a second frame structure supported by said main frame structure, drums rotatably mounted in the second frame structure in spaced relation to each other, a sprocket associated with one of said drums and rotatable therewith, horizontal plates mounted on the second frame structure and extending tangentially between the drums at the top and bottom thereof, an endless chain of rollers arranged to travel on said drums and intermediate plates, an outer endless carrier including a plurality of brackets arranged to travel on the chain of rollers, pivots connecting the brackets in the outer carrier, means on certain of said pivots arranged for engagement by the teeth of the sprocket, upper and lower guide means, means mounted on certain of said pivot pins arranged to cooperate with said guide means, abrasive elements mounted in the brackets of the outer chain, and means for actuating the sprocket to drive the carrier. 45 50 55 60

8. In a grinding device, a main frame structure, a second frame structure supported by said main frame structure, means for adjusting the second frame vertically with respect to the main frame, drums rotatably mounted in the second frame structure in spaced relation to each other, sprocket associated with one of said drums and rotatable therewith, horizontal plates mounted on the second frame structure and extending tangentially between the drums at the top and bottom thereof, an endless chain of rollers arranged to travel on said drums and intermediate plates, an outer endless carrier including a plurality of brackets arranged to travel on the chain 70 75

- of rollers, pivots connecting the brackets in the outer carrier, means on certain of said pivots arranged for engagement by the teeth of the sprocket, upper and lower guide means, means 5 mounted on certain of said pivot pins arranged to cooperate with said guide means, abrasive elements mounted in the brackets of the outer chain, and means for actuating the sprocket to drive the carrier.
- 10 9. In a grinding device, the combination with drums rotatably mounted in spaced relation to each other, of an endless chain of rollers arranged to travel on said drums, an outer endless carrier including a plurality of brackets arranged to 15 travel on the chain of rollers, and abrasive elements mounted in the brackets of the outer carrier.
- 10 10. In a grinding device, the combination with drums rotatably mounted in spaced relation to 20 each other and horizontal plates extending tangentially between the drums at the top and bottom thereof, of an endless chain of rollers arranged to travel on said drums and the intermediate plates, an outer endless carrier arranged to 25 travel on the chain of rollers, and abrasive elements carried by said outer endless carrier.
- 11 11. In a grinding device the combination with drums rotatably mounted in spaced relation to each other, of sprockets associated with said 30 drums and rotatable therewith, horizontal plates extending tangentially between the drums at the top and bottom thereof, an endless carrier arranged to travel about the drums and said intermediate plates, means on said endless carrier arranged for engagement by the teeth of the sprockets, guide means, means on certain of said means engaged by the teeth of the sprockets arranged to cooperate with said guide means, and means for actuating at least one of the drums 35 and associated sprocket to drive the carrier.
- 12 12. In a grinding device the combination with drums rotatably mounted in spaced relation to each other, of sprockets associated with said drums and rotatable therewith, horizontal plates 40 extending tangentially between the drums at the top and bottom thereof, an endless chain of rollers arranged to travel on the drums and said intermediate plates, an outer endless carrier arranged to travel on said chain of rollers, means 45 on said endless carrier arranged for engagement by the teeth of the sprockets, guide means, means on certain of said means engaged by the teeth of the sprockets arranged to cooperate with said guide means, and means for actuating at least 50 one of the drums and associated sprocket to drive the carrier.
- 13 13. A grinding device including a pair of members mounted in spaced relation and having drum surfaces, a chain of rollers surrounding said 55 members and adapted to ride on said surfaces, an endless carrier adapted to ride on the rollers of

said chain, abrasive means carried by said carrier, and means engaging said carrier to effect movement thereof.

14. A grinding device including a pair of members mounted in spaced relation and having drum surfaces, a chain of rollers surrounding said members and adapted to ride on said surfaces, an endless carrier adapted to ride on the rollers of said chain, the carrier including a plurality of brackets with pivot means therebetween, abrasive means carried by said brackets, and means for actuating the carrier including a driving element engaging said pivot means.

15. For an endless abrasive-brick carrier, a bracket member having means for pivotal attachment thereto with other similar brackets in the carrier, an abrasive device comprising abrasive material and a supporting member, the supporting and bracket members being provided with separable interlocking portions, whereby the abrasive device may be removed from the bracket member, and a displaceable element normally preventing separation of said bracket and supporting members.

16. In a machine for grinding a rail of a trackway, a frame structure for supporting the machine in rail grinding position, a pair of spaced support members adjustably carried by the frame structure for movement toward and away from the rail to be ground, an endless carrier surrounding said members, a series of separate abrasive devices mounted on the carrier, the support members being curved to provide curved runs in the path of movement of the carrier, guide means providing a straight run for the carrier adjacent said rail and below a position of tangency with respect to the curved runs, an end of said guide means being terminated in spaced relation with respect to a curved run to provide a run which is inclined with respect to the rail at a low angle, and guide means for the inclined run of said carrier.

17. In a machine for grinding a rail of a trackway, a frame structure for supporting the machine in grinding position with respect to the rail to be ground, a pair of spaced support members carried by the frame structure, an endless carrier surrounding said members, a series of separate abrasive devices mounted on the carrier, the support members being curved to provide curved runs in the path of movement of the carrier, guide means providing a straight run for the carrier adjacent said rail and below a position of tangency with respect to the curved runs, an end of said guide means being terminated in spaced relation with respect to a curved run to provide a run which is inclined with respect to the rail at a low angle, and guide means for the inclined run of said carrier.

60 HENRY J. PERAZZOLI.
